1

The present invention relates to a new and distinct variety of grapevine, named "Kat.E.Lin", which was discovered by us as a mutant of the Concord (Labrusca) variety, said discovery having occurred in our vineyard at Smithville, Ontario, Canada.

This new grape is characterized by early ripening fruit which matures well before frost in Ontario, Canada; by its ability to withstand temperatures below -18° C.; by its large open bunches of fruit which are easily sprayed and mechanically harvested; by its fruit colour which is dark maroon red with a heavy bloom; by its large shouldered bunches; by its very high sugar content; and by its excellent rating for sweet dessert wine, jelly and table use.

THE DRAWINGS

FIG. 1 is a drawing of a leaf showing the various parts measured and angles calculated for the numerical comparison of leaf shapes as outlined in the detailed description of the foliage (reference: Cépages et Vignobles de France, Tome I - Les Vignes Américaines; Imprimerie Charles Déhan, Paris, 1988).

FIG. 2a is a tracing of the petiolar sinus of type leaves of Kat.E.Lin.

FIG. 2b is a tracing of the petiolar sinus of type leaves of Concord.

FIG. 3a is a tracing of the dentations of type leaves of Kat.E.Lin.

FIG. 3b is a tracing of the dentations of type leaves of Concord.

FIG. 4 is a photograph of the leaves of Kat.E.Lin and Concord to illustrate the range in leaf shape.

FIG. 5 is a photograph of the leaves of Kat.E.Lin and Concord to illustrate the colour and texture of both surfaces.

ABSTRACT

A new and distinct asexually reproduced grapevine variety, as illustrated and described, is vigorous and highly productive, ripens early before frost, withstands temperatures below -18° C., fruits in fairly large open bunches with large shoulders, the fruit being red to dark maroon/oxblood red with a heavy bloom and having one of the highest Brix or sugar test of any labrusca grape reported in the Grape and Wine Research Summary for 1984 published by the Horticultural Research Institute of Ontario, Vineland Station, Ontario, Canada. The plant is resistant to mildew and does not require thinning. The fruit has a long shelf life and has proven to be excellent for jam, jelly and sweet, dessert wine.

6 Drawing Sheets

2

FIG. 6 is a photograph of leaves and canes of Kat.E.Lin and Concord to illustrate the differences in colour and dimension.

FIG. 7 is a photograph of the clusters of Kat.E.Lin and Concord to illustrate the range in shape and the differences in colour.

FIG. 8 is a photograph of the clusters of Kat.E.Lin and Concord to illustrate the differences in colour.

FIG. 9 is a photograph of the seeds of Kat.E.Lin and Concord to illustrate the differences in colour, size and shape.

DETAILED DESCRIPTION

The present mutant was discovered in our own vineyard at Smithville, Ontario, Canada in the 1960 growing season among twenty-five acres of Concord grapes which had been planted in the year 1925. It took three years for the original vine to bear fruit. Cuttings were taken in the fall of 1960, planted in 1961 and bore fruit in 1964. Propagation was carried out by taking two or three node cuttings in February, bundling in 10's and burying upsidedown in the ground, covered by two inches of soil. Cuttings were replanted in a nursery row eight weeks later.

Comparison With A Standard (Concord) Grown at the Same Relative Location

All colour references are from The Royal Horticultural Society Colour Charts (The Royal Horticultural Society, London, copyright 1966), henceforth called R.H.S.C.C.

All foliage measurements and description are based on 10 leaves from the mid-section of a mature cane and follow the ampelographic definitions of Galet (P. Galet, Cépages et Vignobles de France, Tome I - Les Vignes Américaines; Imprimerie Charles Déhan, Paris, 1988). See FIG. 1 for general terms of reference.

<u>Surface markings</u> <u>dorsal</u>	
yellow brown (RHSCC 199A) gently rounded shoulders no distinct dorsal groove	grey brown (RHSCC 197A) heavy rounded shoulders, club shaped with distinct dorsal groove distinct neck to beak beak uniformly coloured
gradual tapering to beak dark red/brown at basal tip of beak (RHSCC 200B)	

The new mutant is vigorous and productive and ripens well before frost. Fruiting wood withstands temper-

atures below -18° C. It produces fairly large open bunches with large shoulders. The fruit is red to dark maroon/oxblood red. It has high dissolved solids (Brix readings), exceeding those of many varieties noted in

5 the Grape and Wine Research Summary for the year 1984, published by the Horticultural Research Institute of Ontario, Vineland Station, Ontario. The plant is resistant to mildew and does not require thinning to attain commercially acceptable berry size or fruit quality. The

10 fruit has a long shelf life and has proven an excellent product for jam, jelly and sweet dessert wine.

We claim:

1. A new and distinct variety of grapevine, substantially as herein shown and described, characterized by excellent vigor and productivity, early ripening, hardiness to below -18° C. temperatures, mildew resistant, long shelf life and high sugar content.
